STRUCTURAL ELEMENT

P. Bobbin Attwell, Seattle, Wash., assignor to I.
F. Laucks, Inc., Seattle, Wash.

Application May 20, 1940, Serial No. 336,272

15 Claims. (Cl. 20—0.5)

The present invention relates to structural elements, such as beams, timbers, girders, spars and the like, and to novel structures in which such elements may be incorporated.

It is an object of the present invention to provide a novel form of beam, fabricated from a plurality of smaller elements and assembled in such manner as to provide a beam having characteristics as to uniformity, strength and rigidity as good or better than the best natural wooden beams of corresponding size.

It is a further object of the invention to fabricate, from a plurality of individual elements, wooden beams and the like of greater size than can be readily found in a single piece in the forests at the present time. Moreover, the invention provides smaller beams or spars of greater uniformity as to weight and strength than can be secured in large quantities from standard lumber. Such uniform beams or timbers are of special utility as spars for aircraft wings.

It is a further object of the invention to provide a novel form of large beam for supporting roof structures of unusually wide span. In accordance with one phase of the invention, wide roof structures are supported from a central supporting area, with the ends of the beams unsupported and the laterally projecting portions of the roof supported only by the outwardly projecting beam ends. Thus, the invention also contemplates a novel form of building wherein the roof is supported by beams made in accordance with the invention.

It is a further object of the invention to provide a supporting beam fabricated from inexpensive materials and having a novel internal structure which imparts great strength and rigidity to the beam and enables the same to support heavy loads over unusually great spans.

It is a further object of the invention to provide a beam which may be constructed by ordinary carpenters from readily available lumber at the place where the beam is to be used, or "on the job," thereby simplifying transportation problems. To this end, the invention provides a beam which may be fabricated from standard boards or planks, such as 2 x 8 or 2 x 12 slabs, glued together in a novel manner, at the place where the beam is to be used, so that bridges, buildings, such as airplane hangars, etc., can be constructed in relatively inaccessible locations.

It is a further object of the invention to provide beams, girders, trusses and the like which are of particular utility for military purposes, in that they may be readily and quickly made up

at the location where they are to be used, from a plurality of easily transportable units. More particularly, the invention provides methods and means whereby an advancing army can quickly fabricate beams and truss members of practically any desired size, on the site, to build or re-build bridges or the like which, for instance, may have been destroyed by a retreating army. The constituent parts of beams, girders or truss members, consisting essentially of standard relatively small wooden planks and glue, such as dry, powdered casein glue, may be readily carried forward by the advancing army, whereas it would be impossible to transport pre-fabricated beams or girders of corresponding size.

In supporting beams, girders or truss members, certain portions thereof, depending upon the direction of the application of the load, are subjected to tensional strains, while other portions are subjected to compression forces. The beam of the present invention has been constructed in recognition of these factors, and special features have been combined in a novel and improved manner to make certain portions of the beam effectively resistant to tensional strains and other portions similarly resistant to compression forces.

In the accompanying drawings and in the following description, a plurality of specific embodiments of the invention are shown and described with considerable particularity, but it must be understood that the invention is not limited to the specific details disclosed, since many modifications will readily occur to one skilled in the art.

In the drawings:

Figure 1 is a side elevation of one form of beam, adapted to be supported at its ends and to support a load intermediate thereof.

Figure 2 is a somewhat diagrammatic side elevation of a second form of beam, adapted to be supported at a central supporting area and to carry the load upon the outwardly projected portions thereof.

Figure 3 is a diagrammatic plan view with a central section broken away, showing an airplane hangar or the like, embodying beams of the general type shown in Figure 2.

Figure 4 is a somewhat diagrammatic vertical section of the hangar shown in Figure 3, and

Figure 5 is an enlarged fragmentary elevation of a portion of the beam shown in Figure 2.

Referring to Figure 1, the beam 10 of the present invention is preferably made up of boards or planks of common sizes, readily available from

lumber yards. The members are arranged horizontally in end to end relation in superimposed layers, and all contacting faces thereof are firmly united by a glue bond, such as a water-resistant casein glue of the self-bonding type. The individual boards or planks, cut as described below, are brushed or otherwise coated with the glue and laid up in a suitable manner and spiked together to hold the layers and individual slabs in firm contact under sufficient pressure to enable the adhesive to set and provide a firm bond. If a water-resistant casein glue of the self-bonding type is used, the bond will be formed in four to eight hours under a minimum pressure, such as can be readily applied by nails or spikes. These glues are well known and are commonly used where the bonding pressure is applied by nailing instead of by clamps.

The beam 10 is adapted to be supported at its ends, as indicated at 11, 12 and the load is normally applied at 13. Hence, the bottom layer or layers, extending substantially one-third of the height of the beam, are subjected to tensional strains, while the layers at the top one-third are subjected to compression forces. Throughout the central zone, the forces are substantially neutral.

In accordance with the present invention, the lower, tension-receiving layers are made up of boards or planks 14 having their ends cut on angular planes to provide a scarfed joint 15, characterized by a substantial overlap of the adjacent boards and a greatly increased gluing area. The amount of overlap or scarf may vary from about six to twelve times the thickness of the slab, a longer overlap being preferable as producing a stronger joint. It is known that a well-glued scarf having a length to thickness ratio of 10 or 12 to 1 of thickness approximates the strength of an unbroken member. Such a joint effectively resists the tensional strains to which the layers are subjected.

Although the angle of pitch of the end faces of the lower planks 14, providing the scarfed joints 15 may be varied, it thus preferably is at least 8 or 10 to 1. That is, for every unit of vertical thickness of each plank, the scarfed end extends longitudinally 8 or 10 units.

The upper, compression-resisting layers 16 are provided with square-cut butt joints 17, glued together as previously described, with the result that compression forces are transmitted squarely from end to end of the individual planks in the compression-receiving layers. For the sake of simplicity, the intermediate layers 18 also may be provided with square-cut, butt joints.

A second form of beam made in accordance with the present invention is shown in Figure 2. This beam preferably functions on the cantilever principle, is supported at a central area and projects laterally in opposite directions to support the load of a roof or the like, the ends of the beam being unsupported. The beam 20 in Figure 2 is shown as a support for the roof of a novel form of airplane hangar, which will be described, reference being had to Figures 3 and 4.

A plurality of such beams 20 are supported at 21, 22 by horizontal plates 23, 24 mounted upon the upper ends of columns 25, 26, the latter being braced by cross-beams 27, 28. From the central supporting area, between the points 21, 22, the beams project laterally at 29, 30, thereby providing a support for roof rafters 31 and a roof 32.

Sliding doors 35 may be supported by any appropriate hanger means secured to the ends of the beams or a finishing strip 36 disposed along

the side edge of the roof and enclosing the ends of the beams.

The beams 20 are supported upon pairs of columns 25, 26, as indicated in Figure 4, in parallel relation, spaced on suitable centers, e. g., 10 ft. centers. Preferably, the ends of the building are closed by suitable walls 37. The sliding door arrangement may be such that substantially the entire sides of the building may be opened, to facilitate the entrance and exit of airplanes or the like.

The central supporting area of the beams may conveniently be used as a base for a monitor building 40, provided with windows 41 and a floor represented diagrammatically at 42, which building may house offices, shops or the like. Moreover, the space between the various supporting columns 25, 26 may be utilized for storage, machine shops or for other purposes.

The beam 20 may be made up of wooden slabs, such as 2" x 10" or 2" x 12" planks, which may be readily obtained from any mill or lumber yard. Douglas fir or long leaf Southern pine combine the qualities of uniformity and strength and are suitable materials.

The planks are laid up in layers as previously described, with the planks in the individual layers in end-abutting relation and with the adjacent top, bottom, and end faces of the adjacent slabs or planks all glued together, to provide a strong bond and to prevent relative sliding movement between the laminations. With a beam of this type, used in a building of the kind shown in Figures 3 and 4, the top layers 45, 46, 47 are placed under tension when the load is applied and the lower layers are placed under compression. Hence, the upper layers are made up of planks having their ends cut on angles sharply disposed to the horizontal, thereby greatly increasing the area of the glue bond between the ends of the planks and providing a scarfed joint, as described above. The angle of pitch of the end faces, again, is preferably 8 or 10 to 1 or greater.

Certain of the lower layers, such as those indicated at 50—55, which are subjected to compression forces when the load is applied, are made up of planks adhesively united as aforesaid, but provided with square-cut ends, providing square, butt joints 56, whereby compression forces in the layers are transmitted squarely from one plank to the next. The intermediate layers may, for convenience, be made from planks also having square, butt joints.

As suggested in Figure 2, in order to increase the strength of the beam and to resist bending thereof, it is sometimes found desirable to apply a plurality of additional tension-resisting layers 57, 58, 59 to the upper faces of the end portions of the beam, between the central supporting area and the extremities thereof. As shown in Figure 1, three layers of progressively decreasing length may be applied, and, as in the case with the aforementioned tension-resisting layers, the individual planks are joined together in end to end relation by glued, scarfed joints, the planes of which are preferably pitched oppositely to those of the layers therebelow. In many cases, however, the extra layers 57—59 applied to the upper surface of the end portions of the beams are unnecessary.

In actual practice, cantilever beams in accordance with the present invention have been constructed having overall lengths of 110 feet. These beams were built up of dressed, 2" x 10"

planks of suitable length, adhesively secured together with the top three layers, as well as the extra layers 51, 58, 59, provided with scarfed joints and the remaining layers with square, butt joints. At the center, there were thirty-six layers of planks, providing a vertical thickness of substantially 5 feet, 2 inches. The beam tapered toward its ends, as indicated diagrammatically in Figure 2, to a thickness of 10 inches at its extremities. In the installation under discussion, the two supporting points were spaced 20 feet apart, thereby providing a span of 45 feet from each point to the adjacent end of the beam. For the sake of clarity, in the accompanying drawings, a fewer number of plank layers are shown, and it must be understood that the invention is not limited to any particular size of beam or dimension of the planks or slabs. A beam of the type described was tested under loads as high as 650 pounds per linear foot, from the central supporting points outwardly. No objectionable deflection was noted, after extensive test periods.

In making the beam, the slabs or planks may be adhesively coated, as stated above, with a suitable glue, for example, water-resistant casein glue, desirably of the self-bonding type. After being coated with such a glue, the planks are secured together by conventional nails or spikes, to hold the layers in firm contact under reasonable pressure, while the adhesive is setting and to obviate the necessity of using large pressure applying clamps, forms or the like. The planks are preferably laid up in a rough form, so as to give the desired pitch or camber to the laterally projecting portions of the beam, beyond the central supporting zone, which facilitates drainage of rainwater on the roof toward the center where it may be carried away by appropriate drainage spouts, not shown. This is of especial advantage in constructing airplane hangars for military purposes in cold climates, so as to obviate any icing-up of the doors.

Beams and girders made in accordance with the present invention have many advantages as compared with steel girders and single-piece, solid wooden timbers. Steel girders are far more expensive and must be fabricated at a steel mill and transported to the place of installation. The transportation costs and difficulties alone, in many cases, make the beam of the present invention more economical and convenient than steel beams. Extremely large wooden timbers, on the other hand, are practically unavailable today, because of the scarcity of large trees. Moreover, trees large enough to provide beams of the size contemplated by this invention, if existent, are usually inaccessible, and transportation problems, again, are encountered.

In the manufacture of certain types of aircraft wings and the like, wooden spars characterized by high strength and great uniformity are essential, but considerable trouble has been encountered in securing such spars from natural wood and the supply is constantly diminishing. The present invention is of particular utility in this field, since the laminations, built up and glued together, as described above, provide a spar structure of maximum uniformity. Any flaws or weaknesses in one ply are counteracted and offset by the adjacent plies and the glue bond. Because of the manner in which the beam is constructed from a plurality of layers, it is impossible for a flaw or weak spot, such as might result from a knot in the wood, to extend com-

pletely through the beam. Hence, the invention is of particular utility where the high uniformity characteristics are desired, such as in aircraft construction.

The invention is not limited to the specific details of construction described above, but covers all constructions coming within the scope of the appended claims and their equivalents. For instance, it is, of course, understood that in the case of members of small section such as the laminated airplane wing spars previously described, relatively thin wood veneers provided with suitable scarfed or butt joints are equivalent to the slabs or planks of dimension lumber used in constructing large structural beams.

I claim:

1. A structural unit, such as a beam, girder or timber, of the type adapted to have portions subjected to tensional strains and other portions subjected to compression forces when in load supporting condition, said unit comprising a plurality of elongated boards or planks horizontally aligned in end to end relation and superimposed in layers with the contacting surfaces thereof adhesively united by a glue bond, the boards or planks in the layers in the portion subjected to tensional strains being connected at their ends by angularly cut, glue-bonded scarfed joints and the boards or planks in the layers in the portion subjected to compression forces being connected at their ends by substantially square-cut butt joints.

2. A beam adapted under load to have a portion thereof subjected to tensional strain and another portion subjected to compression forces, said beam comprising a plurality of wood slabs arranged end to end and superimposed in face to face relation in a plurality of layers, and glue bonds between the adjacent faces and ends of the slabs, the adjacent ends of the individual slabs in a layer in the tension-receiving portion being cut on planes disposed on oblique angles to the top and bottom faces of the slabs and providing glue-bonded scarfed joints to resist the tension in said layer, the adjacent ends of the individual slabs in a layer in the compression-receiving portion being cut on planes disposed substantially at right angles to the top and bottom faces of the slabs and providing square, butt joints, whereby the compression forces in said layer are resisted.

3. An elongated beam of substantial height adapted under load to have substantially one-third of its height subjected to tensional strain and the opposite one-third subjected to compression forces, said beam comprising a plurality of wood boards or planks arranged end to end and superimposed in face to face relation in a plurality of layers, and glue-bonds between the adjacent faces and ends thereof, the adjacent ends of the boards or planks in the layers in the first-mentioned one-third of the height of the beam being cut on planes disposed on oblique angles and providing a glue-bonded scarfed joint to resist said tensional strains, the adjacent ends of the individual boards or planks in the layers in the last-mentioned one-third of the beam being substantially square-cut and providing square, butt joints to resist said compression forces.

4. A beam adapted to resist bending stresses and strains applied in opposite directions to a central portion and to the ends of the beam, comprising a plurality of planks arranged end to end and superimposed in layers with the adjacent top, bottom and end faces of adjacent planks

glue-bonded together, thereby providing an elongated, laminated beam of substantial height, said beam being characterized in that, in the layers thereof subjected to tension under said bending stresses and strains, the ends of the planks are joined with angularly cut, scarfed joints, while, in the portions of the beam subjected to compression, the ends of the planks are joined in square-cut butt joints.

5. An elongated beam adapted to be supported at its ends and to support a load intermediate its ends, comprising a plurality of wood planks arranged end to end and superimposed in face to face relation in a plurality of layers, and glue-bonds between the adjacent faces and ends of the slabs, characterized in that in the lower, tension-receiving layers of the beam, the ends of the adjacent planks are cut on angularly disposed planes providing scarfed joints and that in the upper, compression-receiving layers, the ends of the planks are cut substantially square, providing butt joints.

6. An elongated beam comprising a plurality of wood planks arranged end to end and superimposed in face to face relation in a plurality of layers, and glue-bonds between the adjacent faces and ends of the slabs, characterized in that in the upper, tension-receiving layers of the beam, the ends of the adjacent planks are cut on angularly disposed planes providing scarfed joints and that in the lower, compression-receiving layers, the ends of the planks are cut substantially square, providing butt joints.

7. A beam for roofs or the like adapted to be supported from a central portion and to be unsupported laterally therefrom to its edges, said beam comprising a plurality of elongated wooden slabs horizontally arranged in end to end relation in layers superimposed upon each other, and securing means rigidly connecting all of the adjacent faces of all of the slabs, said layers being of progressively increasing length from the bottom of the beam toward the top, the layers at the bottom being relatively short and only of sufficient length to span the central supporting area.

8. A beam for roofs or the like adapted to be supported from a central portion and to be unsupported laterally therefrom to its edges, said beam comprising a plurality of elongated wooden slabs horizontally arranged in end to end relation in layers superimposed upon each other, and glue-bonds between the adjacent faces of the slabs, said layers being of progressively increasing length from the bottom of the beam toward the top, the layers at the bottom being relatively short and only of sufficient length to span the central supporting area while the slabs in certain of the upper layers extend continuously from end to end of the beam.

9. A beam for roofs or the like adapted to be supported from a central portion and to be unsupported laterally therefrom to its edges, said beam comprising a plurality of elongated wooden slabs horizontally arranged in end to end relation in layers superimposed upon each other, and glue-bonds between the adjacent faces of the slabs, said layers being of progressively increasing length from the bottom of the beam toward the top, the layers at the bottom being relatively short and only of sufficient length to span the central supporting area while the slabs in certain of the upper layers extend continuously from end to end of the beam, the slabs in the last-mentioned tension-receiving layers being

joined together at their ends by glue-bonded scarfed joints, while the slabs in the lower, pressure-receiving layers are joined at their ends by substantially square-cut butt joints.

10. A beam comprising a plurality of glue-bonded wooden planks arranged end to end in superimposed layers, the planks in the tension-receiving layers being joined at their ends by glue-bonded scarfed joints to resist endwise separation under tensional strains, and the planks in the compression-receiving layers being joined by substantially square-cut end-abutted joints to prevent relative endwise movement thereof under compression forces.

11. A beam comprising a plurality of elongated wooden slabs arranged in end to end relation and superimposed in a plurality of layers and all secured together by glue-bonds between the adjacent faces thereof, said beam, on the face thereof which is subjected to tensional strains when bending forces are applied, being provided with a plurality of additional layers of wood slabs adhesively united thereto, the individual slabs in the last-mentioned layers being secured together in end to end relation by angularly cut, glue-bonded scarfed joints.

12. A cantilever beam for roofs or the like adapted to be supported from a central area and to be unsupported from that area outwardly to its ends, said beam comprising a plurality of elongated wooden slabs arranged horizontally in end to end relation and superimposed in a plurality of layers all secured together by a glue-bond between the adjacent faces, whereby, when loads are applied to the ends of the beam, the slabs in the upper layers are subjected to tensional strains, and a plurality of additional, tension-resisting slabs applied to the upper face of the beam, adhesively united thereto and extending from the margins of said central supporting area outwardly to the ends of the beam, the individual slabs in the last-mentioned layers being joined together at their ends by angularly cut scarfed joints.

13. In a building, such as an airplane hangar or the like having end walls and unobstructed open sides, a roof and means for supporting the same from a central supporting area, said means comprising a plurality of spaced parallel beams projecting from said area in opposite directions toward the open sides of the building, said beams each comprising a plurality of elongated wood planks arranged in end to end relation in a plurality of superimposed layers and all secured together by glue-bonds between the adjacent faces thereof, the planks in the upper, tension-receiving layers of the beam being joined at their ends by angularly cut, glue-bonded, scarfed joints.

14. In a building, such as an airplane hangar or the like having end walls and unobstructed open sides, a roof and means for supporting the same from a central supporting area, said means comprising a plurality of spaced parallel beams projecting from said area in opposite directions toward the open sides of the building, said beams each comprising a plurality of elongated wood planks arranged in end to end relation in a plurality of superimposed layers and all secured together by glue-bonds between the adjacent faces thereof, the planks in the upper, tension-receiving layers being joined at their ends by angularly cut, glue-bonded, scarfed joints while the planks in the lower, compression-receiving layers are joined at their ends by square-cut butt joints.

15. A roof for a building, such as an airplane hangar or the like which has substantially unobstructed open sides and a centrally positioned, longitudinally extending roof-supporting structure, said roof comprising a plurality of spaced parallel beams projecting from said supporting structure in opposite directions toward the open sides of the building and a continuous roof covering carried by said beams, said beams each

comprising a plurality of elongated wood planks arranged in end to end relation in a plurality of superimposed layers and all secured together by glue-bonds between the adjacent faces thereof, the planks in the upper, tension-receiving layers of the beam being joined at their ends by angularly cut, glue-bonded, scarfed joints.

P. BOBBIN ATTWELL.
